UNITED STATES PATENT OFFICE.

WILLIAM D. HAMMOND, OF LOS ANGELES, CALIFORNIA.

MEANS FOR VAULT PROTECTION.

1,097,587.

Specification of Letters Patent. Patented May 19, 1914.

Application filed March 27, 1912. Serial No. 686,679.

To all whom it may concern:

Be it known that I, WILLIAM D. HAMMOND, a citizen of the United States, residing at Los Angeles, in the county of Los Angeles and State of California, have invented new and useful Means for Vault Protection, of which the following is a specification.

This invention relates to means for preventing burglars or unauthorized parties from obtaining access to banks, storage or other vaults by breaking through the walls of such vaults, and the main object of the invention is to provide electrical protecting devices for the vaults associated with the vault structure in such manner that the walls of the vault cannot be cut into or damaged without affecting the electrical circuit, and on the other hand the walls of the vault protect the electrical circuit from being tampered with.

Other objects of the invention will appear hereinafter.

The accompanying drawings illustrate an embodiment of the invention, and referring thereto:

Figure 1 is a perspective of a vault partly broken away. Fig. 2 is a diaphragm of one form of electric circuits suitable for use in connection with the invention, said circuits providing for open-circuit and closed-circuit protection, and also visual signals by suitable lamps. Fig. 3 is a diagram showing an electric circuit wherein the signal lamps are energized by current through the protective cable. Fig. 4 is a transverse section of the protective cable. Fig. 5 is a detail perspective, of a portion of the cable with the cement removed, showing the interlinking of the loops of the cable.

Referring to Fig. 1, the wall or casing of a bank or storage vault is indicated at 1, said wall consisting, for example, of cement, concrete or other suitable material, preferably such as to constitute an electrical insulator for the embedded protective cable. The protective cable 2 is embedded or molded in this concrete or cement wall, being strung or looped back and forth within said wall, preferably in both longitudinal and transverse directions, or vertical or horizontal directions, as the case may be, so that it is not possible for any part of the wall to be broken or cut without exposing some part of the conductor.

The cable 2 may consist of a metallic cov-

ering or armor 3, and wires 4, 5 and 6 enclosed within said armor and insulated from one another and from the armor by suitable insulation 7.

The invention is used preferably in connection with a triple protective circuit, such as shown in Fig. 2, where 10 designates the battery for the closed circuit connected by wires 11 and 12 through electro-magnetic indicators or galvanometers 13 and 14 with the respective ends of the wire 5 of the cable 2, a rheostat 15 being included in this circuit so as to regulate the current through the indicators. The open circuit battery 17 is connected by wire 18 to one end of the cable wire 4, the opposite end of the other wire 6 being connected by a wire 19 through a relay 20 to the other side of the battery 17. One of the open circuit wires may be connected by connection 34 to the armor 3 of the cable. Said relay controls suitable signal devices, for example, a visual signal consisting of electric lamps 22 and 23 which are connected in circuits 24 and 25 leading from the battery 26 respectively to the back and front contacts 27 and 28 of the relay 20. A return connection 30 leads from the armature 31 of the relay to the battery so that when the armature is on back contact circuit is closed through lamp 22, which may be a blue lamp, whereas when the relay armature is on the front contact circuit is closed through lamp 23, which may be a red lamp.

The cable above described is set in position in the space in which the wall of the vault is molded, so that it becomes embedded in the cement or concrete walls, the said walls serving to support and protect the cable, and the cable giving indication of penetration or fracture of the walls by reason of the effect of such penetration or fracture on the electric connections constituted by the cable. Thus, if the wire 5 is broken at any point by penetration of the cable, the indicators 13 and 14 in the closed circuits 11 and 12 will show the fact of such opening of the circuits, or if the circuit 5 is grounded at any portion such grounding will be shown by reading of the indicators 13 and 14. If a metallic tool penetrates the cable in such manner as to establish connection between the wires 4 and 6, the relay 20 will operate to shift the signal lamps from the blue lamp to the red lamp connection and the same effect occurs if the wire 6 is grounded with

the armor 3 of the cable, said armor being connected to the other wire 4 of the open circuit by connection 34. Instead of controlling the lamp signals by a relay in an open circuit through the cable, the supply current for the blue or safety lamp may pass through the cable itself, as indicated in Fig. 3, the blue lamp 22 being in this case included in the circuit 4 which passes through the cable and in series connection with a relay 20' whose back contact 32 controls the circuit 33 for the red lamp 23. The battery 26 in this case is connected in the circuit in series with the relay 20' and blue lamp 22 so as to cause said blue lamp to be illuminated as long as the cable wire 4 remains unbroken. On rupture of the cable wire 4, the relay 20' allows the armature 31' thereof to close contact at 32 for the circuit of red lamp 23 which thereupon becomes illuminated by current from battery 26, the supply of current to the lamp 22 being cut off by the rupture of the circuit therethrough.

The loops of the cable, passing in different directions may be interlinked, as shown in Fig. 5, thus binding the wall portion of the cable to the ceiling portion, so that neither can be bent without disturbing the other.

What I claim is:

1. The combination of a vault having a cementitious wall, a flexible metal-armored cable embedded and molded into said wall and bent in a plurality of loops so as to completely surround the interior of the vault, every portion of the wall including looped portions of the cable extending transversely to one another, some of the loops of the cable

being interlinked with other loops arranged transversely thereto to bind the angular portions of the vault together, an insulating conductor within said cable, and a signal circuit connected to said conductor.

2. A vault protecting system, comprising a cementitious inclosing wall, a flexible metal-armored cable embedded in said wall and bent back and forth in loops so as to surround the interior of the vault, said cable comprising a conductor insulated from the armor, a controlling circuit, including signal means, said circuit associated with said conductor and armor whereby the grounding of the conductor with the cable armor when the armor is indented or penetrated by a tool will cause the operation of the signal.

3. A vault protecting system comprising a cementitious inclosing wall, a flexible metal-armored cable embedded in said wall and bent back and forth in loops so as to surround the interior of the vault, said cable comprising a plurality of conductors insulated from each other and from the armor, a controlling circuit having connection with said conductors and including a signal, said conductors being arranged to be forced together when said armor is indented or penetrated by a tool to thereby complete said circuit and effect operation of the signal.

In testimony whereof, I have hereunto set my hand at Los Angeles, California this 19th day of March, 1912.

W. D. HAMMOND.

In presence of—

ARTHUR P. KNIGHT,
F. A. CRANDALL.
